(57) **CLAIM**

The ornamental design for a ratcheting screwdriver, as shown and described.

DESCRIPTION

FIG. 1 is a perspective view of a ratcheting screwdriver showing my new design;

FIG. 2 is a front side elevation view thereof;

FIG. 3 is a rear perspective view thereof;

FIG. 4 is a left side elevation view thereof;

FIG. 5 is a right side elevation view thereof;

FIG. 6 is a top view thereof;

FIG. 7 is a bottom plan view;

FIG. 8 is a perspective view in another direction thereof; and, FIG. 9 is another perspective view thereof, with the blade in an open position.

The broken lines depict portions of the ratcheting screwdriver in which the design is embodied that are not considered part of the claimed design.
